COMBINATION BRUSH HOLDER AND ATTACH- MENT FOR A PAINT CAN

Gerhard F. Uhlig, 1206 Stratford Court,
Del Mar, Calif. 92014

Filed Feb. 25, 1966, Ser. No. 1,181

Term of patent 3½ years

(Cl. D9—2)

Fig. 5

The broken line showing of the paint can rim in FIG. 3 is for illustrative purposes only.

I claim:

The ornamental design for a combination brush holder and attachment for a paint can, as shown and described.
